HANDGRIP FOR BARBER AND BEAUTICIAN CHAIRS

Frank Koenigkramer and Frederick Koenigkramer, Cincinnati, Ohio

Application May 16, 1932, Serial No. 611,469

3 Claims. (Cl. 155—16)

This invention relates to a sanitary and chair protective hand grip adapted for attachment to barber and beautician chairs and the like.

An object of the invention is to provide a grip 5 of the kind described to be used by an attendant in moving such chair from one position to another while engaged in attending a customer.

Another object is to provide such a means which protects the chair against the unsightly 10 and unsanitary marks and smears of cosmetics and the like from the attendant's hands and arms.

Another object is to provide such an attachment which is readily cleansed and restored to sanitary condition after having been so marked 15 and smeared.

Another object is to provide such a device which is adapted for efficient manufacture and readily attachable into operative position.

These and other objects are attained by the 20 means described herein and illustrated in the accompanying drawing, in which:

Fig. 1 is a perspective view of the upper portions of a barber, beautician or similar chair with the means of this invention applied thereto.

Fig. 2 is a rear elevational view of the hand 25 grip of this invention.

Fig. 3 is a cross sectional view taken on line 3—3 of Fig. 2.

The hand grip 5 is, in effect, a corner bracket 30 adapted to be attached, one each, upon one of the upper corner portions 6 and 7 of the back 8 of a chair 9 of the kind described which are usually movable pivotally both in a horizontal and in a vertical plane.

Grip 5 is preferably formed with an integral 35 core or body 10 (Fig. 3) such as of iron, covered by the glazed hard surface coating 11, such as enamel. The grip comprises the top arm 12 adapted to be positioned against the top edge of 40 the corner portion of a chair back, and the side arm 13 adapted to be positioned against a considerable extent of the side edge of the chair back. Formed continuously along one edge of said arms 45 is a flange 14 adapted to be positioned against and secured to the rear of the chair back such as by screws passing through perforations 15, whereby the bracket is operatively positioned. The resulting structure is substantially L-shaped in cross section and adapted to snugly embrace the 50 top corner portions of the chair back.

An integral, upwardly projecting extension 16, 55 substantially coextensive in length with arm 12 and integral therewith, serves as the grip proper, adapted to be grasped by an attendant in effecting pivotal movement of the chair. Extension 16 is preferably formed along the rear edge of arm 12 and may be provided with depressed portions 17 facilitating grasping thereof.

As herein shown the top arm 12 is of rounded 60 formation to snugly embrace the similarly round-

ed corner portions 6 and 7 of the chair shown. It is obvious that other shapes are readily produced to fit properly chair backs of different designs.

The attachments preclude contact of an attendant's hands and arms with the chair, whereby the usual leather or plush chair covering is protected as well as the clothes of the customer which otherwise might easily come in contact with grease smears and the like. Such smears may be instantly and completely wiped off the 70 attachments of this invention. Moreover, the extensions 16 are adapted to space the arms of the attendant from the portions of the chair therebelow. The simplicity of the hand grips adapt them for efficient manufacture and ready 75 positioning.

What is claimed is:

1. A chair protective and sanitary hand grip for barber and beautician chairs and the like and adapted to preclude contact of the hands and arms of an attendant with the top portions of a chair back, said attachment consisting of a readily-cleansable smooth surfaced bracket member 80

adapted to embrace a top corner and adjacent edge portions of a chair back and provided with a flange adapted to lie against and be secured to the rear of the chair back for positioning the grip, and a handle portion projecting outwardly of the body of the grip.

2. A chair protective and sanitary hand grip 90 for barber and beautician chairs and the like and adapted to preclude contact of the hands and arms of an attendant with the top portions of a chair back, said attachment consisting of a readily-cleansable smooth surfaced bracket member 95 adapted to embrace a top corner and adjacent edge portions of a chair back, a rounded extension on the bracket adapted to project outwardly of the chair back for providing a handle to be used in moving the chair, and a flange on the bracket 100 adapted to lie against and be secured to the rear of the chair back for positioning the grip.

3. A chair protective and sanitary hand grip for barber and beautician chairs and the like and adapted to preclude contact of the hands and arms 105 of an attendant with the top portions of the back of a chair of the kind described, said grip comprising a readily-cleansable smooth surfaced bracket member substantially L-shape in cross section and adapted to embrace the top, side and rear edge portions at the upper corner of a chair, an integral extension on the bracket and adapted to project outwardly of the chair for providing a handle to be used in moving the chair, and means for securing the rearwardly positioned part of 110 the bracket to the rear of the chair back.

FRANK KOENIGKRAMER.
